UNITED STATES PATENT OFFICE

120,999

DESIGN FOR A REMOVABLE BOTTLE CLOSURE

James A. Murdock, Chicago, Ill.

Application March 25, 1940, Serial No. 91,226

Term of patent 14 years

To all whom it may concern:

Be it known that I, James A. Murdock, a citizen of the United States, residing at Chicago, in the county of Cook and State of Illinois, have invented a new, original, and ornamental Design or a Removable Bottle Closure, of which the following is a specification, reference being had to the accompanying drawing, forming part thereof.

I claim:
The ornamental design for a removable bottle closure, as shown.

JAMES A. MURDOCK.
